US00D870580S

(12) **United States Design Patent** (10) Patent No.: **US D870,580 S**
(45) Date of Patent: **** Dec. 24, 2019**

(54) **SCALE**

(71) Applicant: **TERAOKA SEIKO CO., LTD.**, Tokyo (JP)

(72) Inventor: **Syuusaku Yokono**, Tokyo (JP)

(73) Assignee: **TERAOKA SEIKO CO., LTD.**, Tokyo (JP)

(**) Term: **15 Years**

(21) Appl. No.: **35/506,039**

(22) Filed: **May 21, 2018**

(80) **Hague Agreement Data**

Int. Filing Date: **May 21, 2018**

Int. Reg. No.: **DM/103556**

Int. Reg. Date: **May 21, 2018**

Int. Reg. Pub. Date: **Nov. 16, 2018**

(30) **Foreign Application Priority Data**

Nov. 27, 2017 (JP) 2017-026302

(51) LOC (12) Cl. **10-04**

(52) U.S. Cl.

USPC **D10/91**

(58) **Field of Classification Search**

USPC D10/83, 91, 87, 88
See application file for complete search history.
